UNITED STATES PATENT OFFICE

2,508,372

PEN RULE

William I. Carlson, Detroit, Mich.

Application July 27, 1945, Serial No. 607,361

3 Claims. (Cl. 242—107)

1

This invention relates to writing device such as pencils, pens, etc. and has for its primary object to provide the combination of a pencil and a steel ruler.

A further object of this invention is to provide a combination pencil and drafting instrument.

A still further object of my invention is to provide a combination pencil and ruler case in which the pencil barrel forms a supporting and securing means for a flexible ruler case.

Other features and advantages will become more readily apparent from the following description and the accompanying illustrative drawings in which:

Figure 1 is an elevational view of my combined pencil barrel and square.

Figure 2 is an enlarged vertical sectional view of the upper end of Figure 1.

Figure 3 is a bottom plan view of a combined barrel cap and ruler case.

Figure 4 is a detail elevation of a ruler barrel, and

Figure 5 is a detail elevational view of a ruler shaft.

In the accompanying drawings as above enumerated and in the following specification, like characters of reference indicate like parts throughout and in which 10, indicates my combined pencil and ruler which consists of a pencil barrel 11, the top 12, of which has a cap 13, with in the lower end 14, of which is fixed the upper end 15, of a housing 16, of a diameter to frictionally engage the inner surface 17, of the wall 18, of the barrel 11. The cap 13, is provided with a bore 19, through which the upper end 20, of a vertical shaft 21, projects, the lower end 22, of which projects through an opening 23, in the bottom wall 24, of the housing 16.

Fixed within the upper end 15, of housing 16, is a cap 25, with an offset portion 26, which forms a female recess 27, within which is adapted to seat the male octagonal enlargement or shank 28, of the shaft 21. The top wall 29, of the offset is provided with a bore 30, through which said shaft 21, projects.

Spaced apart on shaft 21, are integral or fixed flanges 35 and 36, which together with the shaft form a spool 37, upon which one end of a flexible steel ruler 38, is fixed. The width of said ruler is substantially that of the space between flanges 35 and 36, said space being two-thirds that of the length of slots 39, in housing 16 and 40, in barrel 11, which slots align with one another. A spring 34 is disposed on the shaft 20 to space the flange 36 above the wall 24.

Projecting through the said bottom wall 24, is

2

a pin 41, to which is fixed one end 42, of a clock spring 43, the inner end 44, of which seats in a slot 45, in the terminal end 46, of the shaft 21. The slot 46, extends through the upper edge 47, of barrel 11, and the ruler 38, projects through both slots 39 and 40. The flanges 35 and 36, of spool 37, hold the steel ruler 38, against lateral movement relative to barrel 11. The edge 48, of top 13, seats flush with said edge 47, whereby the wall 49, of said barrel forms a straight edge and at right angles to the ruler 38. A scale 50, is provided longitudinally upon said wall 49, and is adapted to coact with the scale 51, of ruler 38, for drafting purposes. A combined pull and stop member 52, is fixed to the outer end 53, of ruler 38.

From the foregoing specification it becomes obvious that when the member 12, is placed seated upon the end 55, of barrel 11, a closure therefor is provided. It is also obvious that when the flexible steel ruler 38, is wound upon spool 37, and the spring 43, unwound, when the ruler is pulled out, the spring is wound up so as to reverse shaft 21, and spool 37, retracting the ruler and re-winding upon its spool, so that the shaft is pushed in against the tension of coil spring to disconnect male member 28, from its seat in the female recess 27. The shaft 21 is normally held in raised position by the spring 34, coiled upon the lower portion of the shaft 21, and between the wall 24, and flange 36.

When the barrel 11, is seated against the edge of a drawing board, or any other edge, and the ruler 38, drawn out, a perfect try square is provided and through scale 50, equally divided spaces 35 may be marked and then lined through the medium of the oppositely disposed edges, of the ruler or arm 38, of the square which I will designate as a whole as 58.

For would-be, or jack-leg carpenters, or in fact 40 for any rough carpentering, cabinet or other such work, my square will answer all necessary purposes. Such workmen lose much time in going to a tool chest or looking up a misplaced square, whereas they must carry their pencil at all times 45 in their pockets, therefore, with my device a ruler, a square and a pencil are always at the finger tips, thereby saving time which means money.

For scholars, draftsmen and others who need 50 the use of such instrument my device will prove just as useful and valuable.

It is thought that persons skilled in the art to which the invention relates will be able to obtain a clear understanding of the invention after 55 considering the description in connection with

the drawings. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters Patent is:

1. In a device of the character described including a tubular casing, a longitudinally slotted housing fixed therein being closed at its lower end and open at its upper end, a centrally apertured cap closure member in the upper end of said housing, an annular offset locking socket in said closure member, a shaft supported in said housing for longitudinal movement having a locking shank thereon adapted to be received in said locking socket, a reel on said shaft, a tape measure secured to said shaft wound on said reel and extending through said slot, a clock spring disposed below said housing fixed thereto and to said shaft, and a coil spring disposed about said shaft between the bottom of said housing and said reel for forcing said shaft shank into locking engagement with said offset locking socket.

2. The subject matter as claimed in claim 1, and manually operable means for releasing said shaft shank from said locking socket for automatically retracting said tape measure into said housing and onto said reel.

3. In a device of the character described including a tubular casing, a cylindrical longitudinal slotted housing fixed therein, a bottom wall for said housing, a centrally disposed bearing recess in the bottom wall, a centrally apertured cap closure member in the upper end of the housing, a shaft supported in the bearing recess and aperture for axial and longitudinal movement therein, a locking socket in said closure member, an annular recess in said socket, a locking shank secured on said shaft for selective engagement within the annular recess, a reel on said shaft, a tape measure on said reel and extending through the slot, resilient means disposed below said housing fixed thereto and to the shaft, and means disposed about the shaft between the bottom of the housing and the reel for selectively urging said shaft shank into locking engagement with the locking socket.
